UNITED STATES PATENT OFFICE

SAMUEL LACHOWITZ, OF BROOKLYN, AND IRVING SCHIFFMAN, OF NEW YORK, N. Y.

DESIGN FOR A WRIST WATCH OR SIMILAR ARTICLE

Application filed January 24, 1933. Serial No. 46,963. Term of patent 7 years.

To all whom it may concern:

Be it known that we, SAMUEL LACHOWITZ and IRVING SCHIFFMAN, citizens respectively of the United States and of Poland, and residents respectively of the borough of Brooklyn, county of Kings, city and State of New York, and of the borough of Bronx, county of Bronx, city and State of New York, have jointly invented a new, original, and ornamental design for a Wrist Watch or Similar Article, of which the following is a specification and the accompanying drawing, form part thereof.

Fig. 1 is a plan view of a wrist watch showing our new design.

Fig. 2 is a side elevation of the same.

The novel design scheme of our present invention consists of a watch case which terminates at each end thereof in a hand or paw, an embodiment of which is shown in the drawing.

We claim:—

The ornamental design for a wrist watch or similar article, substantially as shown and described.

SAMUEL LACHOWITZ.
IRVING SCHIFFMAN.
